UNITED STATES PATENT OFFICE.

LOUIS WAGNER, OF BERLIN, GERMANY, ASSIGNOR TO WHITING-PATTERSON CO., INC.,
A CORPORATION OF PENNSYLVANIA.

DESIGN FOR FIGURED TISSUE PAPER.

Application filed October 28, 1926, Serial No. 19,525, and in Germany July 27, 1926. Term of patent
 $3\frac{1}{2}$ years.

To all whom it may concern:

Be it known that I, LOUIS WAGNER, a citizen of the Republic of Germany, residing in Berlin, Germany, have invented a new, original, and ornamental Design for Figured Tissue Paper, of which the following is a specification, reference being had to the accompanying drawing, forming a part thereof.

In the drawing, the figure is a view of a portion of figured tissue paper, showing my new design.

I claim:

The ornamental design for figured tissue paper as shown.

LOUIS WAGNER.
